UNITED STATES PATENT OFFICE.

RALPH V. SAGE, OF WESTMONT, PENNSYLVANIA.

HOPPER-CAR AND DOOR THEREFOR.

SPECIFICATION forming part of Letters Patent No. 699,819, dated May 13, 1902.

Application filed November 30, 1901. Serial No. 84,212. (No model.)

To all whom it may concern:

Be it known that I, RALPH V. SAGE, a citizen of the United States, residing in the borough of Westmont, in the county of Cambria 5 and State of Pennsylvania, have invented certain new and useful Improvements in Hopper-Cars and Doors Therefor; and I do hereby declare the following to be a full, clear, and exact description of the invention, such as will 10 enable others skilled in the art to which it appertains to make and use the same.

My invention consists of improved construction of freight-cars and doors therefor, with particular reference to what are known 15 as "self-clearing" hopper-cars, from which an ordinary load of minerals or similar materials may be dumped by gravity after opening the doors at the bottom of the hoppers.

Certain of the objects of my invention are 20 to provide a car which will have a very large capacity and at the same time keep the center of gravity of the car and its load at a low elevation with respect to the track, thus conducing to ease and safety in transportation, 25 a form of door with connections and operating mechanism which will suit and coöperate with my improved construction of the car-body, and other improved constructions, as will hereinafter be more fully described.

30 In order to provide a car of great capacity without raising the center of gravity of the car and its lading, I make the sloping ends of my hopper-car in the form of an extended V, which continue downwardly to a point as 35 near the rail as practicable without being dangerous in use, and to close the openings at the bottom of said sloping ends I provide doors of substantially trapezoidal form, deeper near the center of the car than at the 40 sides, these doors being mounted upon hinges at their upper ends and secured together in pairs by means of a transverse beam, to the central part of which is attached a chain or other suitable member for closing and releasing said doors.

45 The sloping bottoms or ends of my improved car are arranged to incline downwardly from each side toward the longitudinal middle line of the car, a cross-section through this bottom having the form of an extended V, while

this V-shaped bottom also slopes downwardly from the ends toward the transverse middle line of the car.

Through the lower portion of the body of my improved hopper-car the center sills extend in a longitudinal direction and are covered by plates forming slopes ending in a ridge at the top in such a way as to discharge any material which may rest upon this portion of the construction, and, similarly, there 60 is another ridge extending transversely at the center of the car, which also serves to discharge the material from these portions toward the doors, the form and arrangement of these longitudinal and transverse ridges in 65 connection with the sloping ends of the cars being such as to divide the lower portion of the hopper into four sections. The two sections of the hopper thus formed, which are on the same side of the transverse center line of 70 the car, are each provided with an opening of trapezoidal form, the upper line of which is approximately level, the ends of which at the center are deeper than those at the sides, and these openings are closed by doors of corresponding trapezoidal form secured together in pairs by a beam, to the central portion of 75 which the operating-chain or other mechanism is attached.

In addition to providing a form of bottom 80 which gives increased capacity without raising the center of gravity of the car and its lading these trapezoidal doors are advantageous on account of the fact that the center of pressure of the load is nearer the center of 85 the pair of doors and the point of attachment of the operating mechanism therefor than would be the case if rectangular doors were used. As the center of pressure is thus nearer the point of application of the forces which 90 close and hold the doors, this form of door may be made lighter than a rectangular door, still remaining of equal strength, and this lightness is of distinct advantage in reducing the dead-load of the car and also naturally 95 cheapens the cost of the door construction.

Having thus given this general description of certain features of my invention, I will now, in order to make my invention more clear, refer to the annexed four sheets of 100

drawings, which form part of this specification, and in which like numbers refer to like parts.

Figure 1 is a plan view of somewhat more than one-half of my improved car. Fig. 2 is a corresponding vertical longitudinal sectional elevation on the line D D of Fig. 1. Fig. 3 is an end elevation. Fig. 4 is a transverse vertical sectional elevation on the line A A of Fig. 2. Fig. 5 is a central transverse vertical sectional elevation on the line B B of Fig. 2. Fig. 6 is a transverse vertical sectional elevation on the line C C of Fig. 2.

Referring now to the characters of reference on the drawings, 1 represents the center sills, shown in this case of channel-section.

2 are the side channels, and 3 is the transverse ridge-support, shown as composed of two angles and a plate. Supports for the central transverse inclined portions of the hopper are marked 4, shown as channels, and other supports for this portion are marked 5, shown as composed of plates and angles. The central transverse inclines are marked 6, said inclines being connected to the longitudinal incline or ridge 9 by the corner connections 7, and similar corner connections 8 secure the transverse central inclines 6 to the car sides 17.

9 is the longitudinal central incline or ridge, 10 is the main hopper-bottom, which slopes downward both longitudinally and transversely toward the center of the car, the transverse slopes of which form a depressed V, as shown, while 11 represents corner connections between said sloping bottom and the longitudinal central incline or ridge 9.

12 represents the corner connections between the sloping bottom 10 and the car sides 17. 13 represents similar connections between the upper end of the sloping bottom 10 and the vertical ends of the car 14, and 15 represents the lower portions of the hopper sides.

16 represents supports and braces for the lower portion of the sloping bottom 10, and secured thereto, as shown, also forming a portion of the seat for the doors.

17 represents the car sides, preferably formed of plates.

18 represents diagonal braces which connect the supports and braces 30 to the car-frame, said supports and braces 30 being attached to the sloping bottom 10, as shown, and further secured at their ends to the side

plates 17 by means of the angle brackets or connections 31. 29, 32, 34, and 37 are other similar supports and braces attached to the under side of the sloping bottom 10, the first named being bent at the ends and secured directly to the side plates 17, as indicated in Fig. 2, while the other supports and braces Nos. 32, 34, and 37 are also attached to the sloping bottom 10 and further secured to other parts of the construction by the connections 33, 35, 36, and 38, as shown. The three upper supports and braces Nos. 29, 30, and 32 on the under side of the sloping bot-

tom are preferably formed of one piece bent in V form and shaped as indicated on Fig. 3, while the supports and braces Nos. 34 and 37 are each made in two sections ending at the sides and near the center sills, as these members could not extend through and be made in one piece on account of the center-sill construction, as may be understood on reference to the drawings.

19 represents doors, the trapezoidal form of which is clearly illustrated in Fig. 5. 20 represents the hinges for same. 21 is a beam which secures two of the said doors together, causing them to move as one piece. 22 is a chain attached to said connecting-beam for operating the doors, said chain being located between the center sills and below the central longitudinal ridge in an open space in such a way that it is free for operation at all times and not obstructed by the lading under any circumstances. 23 is a winding-shaft for the door-chain 22, which winding-shaft is supported in bearings 24, attached to the car-frame. Said winding-shaft may be operated by means of a wrench or crank and held in position for keeping the doors closed in any reasonable or suitable manner—for example, by the use of a ratchet, pawl, and locking mechanism for said pawl; but for the sake of simplicity on the drawings I have not shown these details for operating the winding-shaft thereon, as they may be of any usual construction for this purpose, as may be readily understood.

25 indicates the car-truck, which may be of any usual form or construction.

26 represents inclined braces extending from the corners of the floor-framing to the vertical ends of the cars, as indicated in Figs. 3 and 4. 27 is a corner-plate for connecting said inclined braces to the floor and car-framing, while 28 is an inner transverse brace for the car sides, secured thereto, as shown.

Although I have shown certain of my improvements in considerable detail, I do not limit myself to the exact particulars of construction, arrangement, and sections shown and described, but may use such substitutions and modifications thereof as are embraced within the scope of my invention and as pointed out in the claims.

Having thus given a description of my invention, what I desire to secure by Letters Patent is—

1. A hopper-car provided with a bottom sloping longitudinally from the ends toward the transverse middle line of the car, said bottom also sloping transversely from the sides toward the longitudinal middle line of the car, a cross-section of said transverse slopes having the form of a V.

2. In a hopper-car, a bottom sloping downwardly from both ends, and from both sides in a V shape toward the center, supports and braces secured to the lower sides of said bottom and attached to the adjoining portions of the car construction.

3. In a hopper-car, a bottom sloping downwardly toward the center from both ends, and from both sides in a V shape, supports and braces secured to said bottom and to the adjoining portions of the car construction, said supports and braces being also connected to the floor-framing by intermediate braces.
4. A hopper-car provided with a bottom sloping both longitudinally and transversely toward the center, a cross-section of the transverse slopes having the form of a V and a central incline sloping downwardly in both directions toward the ends.
5. A hopper-car provided with a bottom sloping both longitudinally and transversely toward the middle lines of the car, a central transverse incline sloping downwardly in both directions from the center of the car toward the ends, and a longitudinal central ridge extending downwardly about the central framing, thus forming four compartments at the lower portion of the hopper.
6. In a hopper-car provided with a bottom sloping both longitudinally and transversely toward the center of the car and forming trapezoidal openings at the lower portion thereof, doors of trapezoidal shape adapted to coöperate with said openings.
7. In a hopper-car provided with a bottom sloping both longitudinally and transversely toward the center thereof, doors of trapezoidal form adapted to coöperate with corresponding openings in the lower part of the hopper-bottom, the adjacent doors on each side of the transverse center line being secured together in pairs by a connecting member.
8. A hopper-car provided with a bottom sloping transversely toward the center, doors of trapezoidal form adapted to coöperate with corresponding openings in said bottom, said doors being attached together in pairs by a connecting member, and operating mechanism attached to said connecting member intermediate of said doors for closing and releasing the same.
9. A hopper-car having a bottom sloping both longitudinally and transversely in a downward direction toward the center of said car and forming trapezoidal openings at the lower portion thereof, doors of trapezoidal form hinged to a horizontal support and arranged with their deeper ends adjacent, said doors being adapted to coöperate with the openings aforesaid.
10. In a hopper-car provided with a bottom sloping both longitudinally and transversely toward the center and forming trapezoidal openings at the lower ends thereof, hinged doors of trapezoidal form adapted to coöperate with the openings aforesaid, said doors being secured together in pairs by a connecting member to the intermediate portion of which operating mechanism is attached.
11. A hopper-car provided with a bottom sloping both longitudinally and transversely toward the center, a central transverse incline sloping downwardly in both directions from the center, said bottom having trapezoidal openings at the lower portion thereof, hinged trapezoidal doors arranged in pairs and adapted to coöperate with the openings aforesaid.
12. A hopper-car provided with a bottom sloping both longitudinally and transversely toward the center, a central transverse incline sloping downwardly in both directions from the center, said bottom having trapezoidal openings at the lower portion thereof, hinged doors of trapezoidal form, said doors being secured together in pairs by a connecting member and adapted to coöperate with the openings aforesaid.
13. A hopper-car provided with a bottom sloping both longitudinally and transversely toward the center, a central transverse incline sloping downwardly in both directions from the center, said bottom having trapezoidal openings at the lower portion thereof, hinged doors of trapezoidal form, said doors being secured together in pairs by a connecting member to the intermediate portion of which operating mechanism is attached.
14. A hopper-car provided with a bottom sloping both longitudinally and transversely toward the center, a central transverse incline sloping downwardly in both directions from the center, a central longitudinal ridge sloping downwardly in both directions toward the sides, said bottom having trapezoidal openings at the lower portion thereof, hinged trapezoidal doors arranged in pairs and adapted to coöperate with the openings aforesaid.
15. A hopper-car provided with a bottom sloping both longitudinally and transversely toward the center, a central transverse incline sloping downwardly in both directions from the center, a central ridge sloping downwardly in both directions toward the sides, thus forming four compartments at the lower portion of said hopper each of which compartments is provided with a trapezoidal opening at the lower portion thereof, hinged doors of trapezoidal form arranged in pairs and adapted to coöperate with the openings aforesaid.
16. A hopper-car provided with a bottom sloping both longitudinally and transversely toward the center, a central transverse incline sloping downwardly in both directions from the center, a central longitudinal ridge sloping downwardly in both directions toward the sides, thus forming four compartments at the lower portion of said hopper, each of which compartments is provided with a trapezoidal opening at the lower portion thereof, hinged doors of trapezoidal form secured together in pairs by a connecting member and adapted to act in coöperation with the trapezoidal opening aforesaid.
17. A hopper-car provided with a bottom sloping both longitudinally and transversely toward the center, a central transverse incline sloping downwardly in both directions from the center, a central longitudinal ridge, thus forming four compartments at the lower por-

tion of said hopper each of which is provided with a trapezoidal opening at the lower portion thereof, hinged doors of trapezoidal form secured together in pairs by a connecting member, and operating mechanism connected to said member intermediate of the doors.

18. A hopper-bottom car provided with trapezoidal doors secured together in pairs by a connecting member, and mechanism for operating the same attached to said member intermediate of said doors.

19. A hopper-bottom car provided with hinged trapezoidal doors arranged with their deeper ends adjacent and secured together as a pair by a connecting member attached thereto, and operating mechanism connected to said member intermediate of said doors.

20. A hopper-bottom car provided with trapezoidal doors secured together in pairs by

a connecting member, the deeper ends of said trapezoids being adjacent, a chain attached to said member intermediate of the doors aforesaid, and means for operating said chain.

21. A hopper-bottom car provided with a pair of trapezoidal doors arranged with their deeper ends adjacent, said doors being secured together by a connecting member attached thereto, a chain connected to said member intermediate of said doors, a shaft for winding said chain and means for operating and locking said shaft.

In testimony whereof I hereto affix my signature in the presence of two witnesses.

RALPH V. SAGE.
